UNITED STATES PATENT OFFICE.

PATRICK J. HODGINS, OF KANSAS CITY, MISSOURI.

DESIGN FOR A BADGE.

Application filed October 23, 1925. Serial No. 15,232. Term of patent 14 years.

To all whom it may concern:

Be it known that I, PATRICK J. HODGINS, a citizen of the United States, residing at Kansas City, in the county of Jackson and State of Missouri, have invented a new, original, and ornamental Design for Badge, of which the following is a specification, reference being had to the accompanying drawing, forming part thereof, wherein:—

Figure 1 is a front elevation of the badge; and

Figure 2 is a vertical sectional view showing in dotted lines one means of attachment to a garment, or other object.

Fig. 3 is an edge view of the badge.

I claim:

The ornamental design for a badge, as shown.

PATRICK J. HODGINS.
